CAP REMOVING SOCKET WRENCH

Herman J. Halm, Toledo, Ohio

Application August 5, 1944, Serial No. 548,227

1 Claim. (Cl. 81—3.34)

1

This invention relates to a socket wrench.

This invention has utility when incorporated as a socket wrench, whereby tight-sealing and release therefrom of a can closure cap may be had with this helpful purpose tool quickly available with convenience from three positions of association with the container: (1) an out-of-use or anchoring position sufficiently local to the screw cap to be handily shifted to (2) socket wrench position upon the cap to clear such from the container opening and then as freed from the cap to be (3) oriented and serve as a pouring spout as its throat is snapped into the container opening rendered accessible upon removal of the cap.

Referring to the drawings:

Fig. 1 is a plan view of a container having a socket wrench tool of the invention embodiment mounted therewith, with broken away portions at the right of the tool;

Fig. 2 is a plan view of a container having the socket wrench tool of Fig. 1 in screw cap engaging position, with a portion of the tool, at the lower left, broken away;

Fig. 3 is a side elevation of the socket wrench of Figs. 1, 2, in oriented position, as thrust into the container opening exposed by removal of the screw cap, and the container tilted to pouring position through the wrench now serving as a spout, the re-entrant top of the container here being broken away to show a tool-receiving countersink instead of an upstanding boss as in Fig. 1, also there being in this Fig. 3, a broken away portion of the neck at the lower right to show in section external screw thread neck of the container opening as providing a seat for the tool; and

Fig. 4 is a section, on an enlarged scale through the socket wrench, on the line IV—IV, Fig. 2.

A container 1 is shown with a screw cap 2. In the area of the container or can top away from the cap 2 as closing the normal filling and discharging opening to the container, is an upstanding boss 3 in somewhat similar dimension to that of the cap 2 exterior. The boss 3 provides a seat upon which may be placed, detachably, an embodiment of the socket wrench tool of the invention herein.

A container 4 (Fig. 2) has a screw cap 2 for turn assembly upon externally threaded neck 5 (Fig. 3) about filling and discharging opening 6 of the container 4 in its top countersink wall 7. The container 4, in its top 7, spaced from the neck 5, has an additional countersink or depressed seat forming portion 8. This seat 8 provides an anchorage or mounting in out-of-use position for

the tool of the invention herein, located somewhat as the projection or boss 3 for the container 1 (Fig. 1).

The device of the invention herein is a socket wrench tool shown of sheet metal and approximately uniform thickness throughout in its integral extent. Considering this tool in connection with the container 4, there is an integral collar or reinforcing flange 9 endless about an opening 10. The outer or free end of this ring or collar 9 has a bevel or chamfered edge 11 to permit ready and snug slipping into the seat 8 in thereby locating the tool in the depressed top 7 area not to extend above the bounding rim 12.

Outwardly from the other end of this cylindrical collar 9, there is an approximately flat base or deck portion 13 from which extends concentrically of the ring 9, a second flange section cylindrical in its extent of beyond 180°. This second section 14, as of arc extent to have its knurled inner face 15 provide socket wrench engagement for the complementarily knurled periphery of the cap 2, has a pair of converging extensions 16 from a tapered connecting bottom 17 extending at an acute angle from the base 13. The extensions 16 with the connecting portion 17, have a common end to approximate a plane 18. In the normal use of this tool, this outward extension 16, 17, 18, serves as a handle for the socket wrench 13, 14, which has reinforcement collar 9, also providing for out-of-use placement of the tool with the container. Supplementally, when the socket wrench tool has achieved removal of the independent screw cap 2 from the container to expose the opening 6, then upon orienting the tool the reinforcing collar 9, at its edge 11 may have frictional engagement, as thrust into the throat of the opening 6 outer terminus.

It is to be noted that the flat deck or ring 13 which determines the back or depth for the socket wrench portion or section 14, has oppositely therefrom the flange or collar 9 as a reinforcement. The collar 9, accordingly has a multiple purpose herein. As coacting with the countersink or seat 8, the tool is anchored in position for ready access when its use may be required. When the short-of-full-annular extent section 14 is seated over the screw cap 2 as a crown therefor, additional rigidity is imparted thereto by the collar 9 to render the otherwise rather frail thin tool sufficiently substantial to hold up for the work as a wrench. The outwardly extending taper portion, filling in the section 14 for a full annular extent, is a handle 16, 17, for the socket wrench. The inner face 15 is crimped,

knurled, roughened, or specially configured to register against turning relatively to the cap 2. As the cap 2 is removed from the container neck 5 to expose the opening 6, this versatile tool need not be discarded, but the collar 9 has a snug holding mounting as thrust into the top of the opening 6. The handle 16, 17, is now in other-side-up position for the channel, to serve as a pouring spout, in the removal of contents from the container 4.

Upon completion of the pouring operation, the tool may be readily disconnected from spout-forming position; the cap 2 located over the opening 6; the tool as a wrench, reversed from the pouring relation, may serve to tighten the cap 2, and then be snapped into the countersink 8 as there held by the collar 9.

Practical and commercial advantages follow throughout herein. The shipping packages or cartons for a plurality of containers retain simplicity, with no extra space or care for handling in or out. The tool as developed is in conformity with maintenance of a manufacturing schedule and requirements, which may be as current, or adapted to special conditions.

What is claimed and it is desired to secure by Letters Patent is:

A channel-shaped sheet metal socket wrench comprising an integrally formed handle and socket head, said head being cylindrical and having an apertured flat base and a continuous

reinforcing flange extending upwardly at the aperture of said base, said flat base extending downwardly at an acute angle longitudinally of the wrench to form said handle, a work engaging flange of more than 180° extending downwardly from the periphery of the head and the side edges of the handle, said last named flange being internally knurled at the wrench head and having its edge lying in a common plane intersecting the handle end.
